SNAP SWITCH

Robert H. Bentley, Hartford, Conn., assignor to
 The Arrow-Hart & Hegeman Electric Co.,
 Hartford, Conn., a corporation of Connecticut

Application June 9, 1950, Serial No. 167,135

12 Claims. (Cl. 200—67)

1

This invention relates to electric switches. More particularly it relates to electric snap switches.

In some uses of electric switches it is necessary to have an operating member or spindle extend out the side of the casing since the conditions of use prohibit the placing of the operating lever at the top casing. Also it is sometimes needful that the mechanism be entirely enclosed and that the operating spindle may extend through an aperture in its enclosure only large enough to admit its passage. Additionally there are occasions when operation of the switch in less than the usual angle of movement of the actuating lever is necessary.

Therefore it is an object of my invention to provide a novel form of electric switch of the over-center type in which the operating spindle extends from the side of the casing and in which the casing completely seals the mechanism so as to make it dust-free without the need of packing or gaskets or other additional elements.

Another object of my invention is to provide in a snap switch of the foregoing type the means for positively moving the switching member after the operating spindle or element has been moved through a small angle, thus positively to start the switching element on its way after the actuating member has moved through less than the normal angle of movement for such a mechanism.

Another object is to provide simultaneous movement of the actuating means and the switching member toward overcenter position after about half-travel of the actuating means so as to cause switch operation on movement of the actuating means through a lesser angle than in conventional overcenter mechanisms.

Another object of my invention is to provide an electric switch of the foregoing type in which the parts may mainly be stamped from sheet metal and may be inexpensively manufactured and assembled.

Other objects and advantages of the invention will appear as it is described in connection with the accompanying drawings.

In the drawings:

Fig. 1 is a longitudinal section view taken along line 1—1 of Fig. 2 of a switch embodying the principles of my invention;

Fig. 2 is a transverse section view taken along line 2—2 of Fig. 1;

Fig. 3 is a detail view showing in end elevation the left-hand spindle assembly of the switch illustrated in Figs. 1 and 2, certain parts being in section and certain others being broken away for clearness;

2

Fig. 4 is a detail elevation view looking into the right side of Fig. 3;

Fig. 5 is a detailed plan view partly in section illustrating only the switch spindle and the location thereon of the contact support, the operating member therefor and the positive kick-off member;

Fig. 6 is an exploded perspective view of the parts illustrated in Fig. 3 except the contact element.

Referring to the drawings, all parts of the switch mechanism are mounted on an operating spindle, some loosely and some fixedly so as to turn with the spindle as will hereinafter more fully appear. The spindle is made in two like halves 18' and 18'', which are joined rigidly together. The spindle and all parts mounted thereon are confined within a dust-proof insulating casing comprising top and bottom sections 10 and 12 which preferably are hollowed out and molded from insulating material so as to cooperate with one another. The switch spindle halves 18', 18'' are mounted in semi-circular bearing recesses, one-half 10b being in the top and the other half 12b being in the bottom section of the casing at the adjacent edges thereof in registering position. (See Fig. 2.) Thus when the casing halves 10 and 12 are joined together they form circular bearing openings for the switch spindle halves.

The outer ends of the spindle halves extend beyond the casing walls and are preferably formed with flattened end portions 18x which may be engaged with any suitable operating means exterior of the casing by which the spindle may be oscillated.

It is often necessary to use switches of this sort in connection with gasoline pumps. Therefore it is essential that they be entirely enclosed and dust-proof also. By having the switch spindle extend through the side of the casing and having its bearing aperture one-half in the top and one-half in the bottom of the casing, it is possible to almost hermetically seal the casing thus making the switch useful in places where the conventional type of toggle switch would be unsuitable because of its large and open aperture which permits the entrance of fumes and dust quite freely.

The inner ends of the spindle are formed with a reduced neck, 18n (Fig. 2) having two flat parallel side portions (Fig. 1). On each of the necks 18n are mounted identical rocker elements 20', 20'', which are preferably stamped from sheet metal material with a central aperture to fit over and snugly upon the neck 18n so as to cause the spindle and rocker elements to turn together. The ends of the necks 18n are peened over upon

the rocker elements to rigidly secure them upon the spindle halves.

As may be seen from Fig. 6 arms of each of the rocker elements lie on opposite sides of the spindle opening 20a. In the ends of the arms are formed holes to receive spacing elements 24 which may be formed from metal rods with reduced end portions to fit in the holes of the rocker elements. The end portions of the spacer elements 24 are peened over against the surfaces of the rocker elements 20 and thus hold the rocker elements together rigidly as a single unit. Since the ends of necks 18n of the spindle 18' and 18'' are also peened over upon the surfaces of the rocker elements, the spindle halves and rocker elements thus become a single unit.

Also mounted upon the necks 18n of the spindle halves and next to the rocker elements but outwardly of the spindle axis are positive kick-over elements 19', 19'' which preferably are stamped from sheet metal into the form best illustrated in Fig. 6. In the center of these elements is punched an aperture to fit snugly over the neck 18n of the spindle so that the kick-over element will be revolved with the spindle. The kick-over elements each have an extension bent at right angles to the plane thereof from its periphery to form a kick-over lug 19k whose purpose will herein-after more fully appear.

The mid-portion of each of the spindle halves 18', 18'', is cylindrical and mounted on them respectively are similar oscillating switch arms 22', 22'', which preferably are stamped from sheet metal into the form best indicated in Fig. 6. The switch arms 22', 22'' are joined together at their lower ends by a transverse strut 23 whose ends pass through apertures formed therein and are peened over to unite the arms together for oscillation as a unit, which will sometimes hereinafter be referred to as the switching member 22.

Also mounted upon the mid-section of the spindle halves are contact-supporting insulators in the form of molded insulation discs, 30, 31, having laterally extending hubs of reduced diameter 30h and 31h on which are mounted bridging contacts 32 and 33 in such a manner as to turn with said insulating contact-supporting members 30 and 31.

In order to cause the contact-supporting members 30 and 31 to rotate with the oscillating switch arms 22' and 22'', a pair of parallel rectangular apertures such as 30a (Fig. 6) are provided in the radial faces of the supporting members 30 and 31 to receive parallel wings 22w formed upon and pressed at right angles to the plane of the oscillating members 22', 22''.

To cause the switching member 22 to move with a snap action, an overcenter spring 15 is compressed and coiled about a spring-supporting member 14 which is preferably stamped from sheet metal with a bifurcated end to straddle the strut 23. A square washer 16 is pressed upon the strut 23 by the lower end of the spring 15, the washer being provided with a slot (not visible) extending transversely to receive the bifurcations of the spring support 14. At the upper end of the spring support 14 is another square washer 17 (also slotted like washer 15) which is pressed by spring 15 against the shoulders 14a, 14b laterally extending from and formed upon the upper end of spring supporting member 14. Washers 16 and 17 are preferably of width equal to the distance between switching arms 22', 22'' so as to keep the spring support 14 centered as the

washers and support move between the arms 22', 22''.

In order to cause compression of the spring 15 and then to swing it and its support 14 across center, and thereby to actuate the switching member 22 with a snap action, I provide a stamped sheet metal operating lever 26, the form of which may be observed from Fig. 1. This operating lever has a circular enlargement 26a on its lower end, which presses against the washer 17. The upper end of the operating lever is pivoted upon a bearing pin 28 which is seated in the bearing recesses 28b molded in the inside of the casing cover.

The operating member 26 is located between the two stampings 20' and 20'' which make up the rocker member and can pivot between them about its own pivot 28 in order to move the over-center spring assembly.

As readily appears in Fig. 1 and as will be further explained below, the vertical pressure components of spring 15 act on the lever 26 to hold the bearing pin 28 seated in the bearing recesses 28b. Hence those bearings can be open. This facilitates the molding of the casing cover and the assembly of the parts of the switch together.

In order to oscillate the operating lever 26 about its pivot 28, a stud or drive pin 27 is secured fixedly between the two identical stampings 20' and 20'', which make up the rocker member. The stud 27 preferably is formed from a metal rod having reduced ends received in holes such as 20h in the rocker member 20. (See Fig. 6.) The larger central portion of the drive pin 27 is adapted to slide within and engage the sides of an elongated opening 26h in the operating member 26.

In order to insure movement of the switching member 22 and at the same time to accelerate the overcenter action so as to accomplish switch operation on movement of the operating lever through a smaller angle than usual, the positive kickover elements 19', 19'' are provided. They cooperate with the switching member 22 in the following way. At the top of the switching arms 22', 22'' there is provided an arcuate surface terminating at the shoulders 22s. The kick-over lug 19k of the hereinbefore described positive kick-over member 19 is adapted to move in a parallel arc over said arcuate surface and to abut or strike against one or the other of the shoulders 22s as the switch spindle is rotated. The kick-over member is so located with respect to the switch spindle that when the spindle is in either of its normal positions of rest, the kick-over lug 19k will be located about in the center of the arcuate surface between the shoulders 22s as may be observed from Fig. 4. Thus after the switch spindle has been moved through approximately half of its full travel from one position of rest to another, the kick-over lug 19k will abut one of the shoulders 22s to start the movement of the switching member 22.

With the foregoing the operation of the device will be explained. Any suitable actuating means may engage with the extending end 18x of the switch spindle, either at one side or the other, or both, of the switch casing. Such actuating means upon rocking the spindle will cause the rocking member 20 (its arms 20', 20'' and driving pin 27 moving as a unit with the spindle) to rock about the spindle axis. Such rocking motion will carry the drive pin 27 (referring to Fig. 1) in a counter-clockwise direction. This movement of the pin by its engagement with the slot 26h in the operating

member 26, causes the operating member 26 to move in clockwise direction about its fixed pivot pin 28. The clockwise movement of the operating lever will cause compression of the spring 15 by reason of the end of the operating lever pressing upon the washer 17 as it usual in overcenter spring mechanisms.

After the spindle 18', 18'' and rocker 20 have turned through about half the full angle of movement (or in the example illustrated about 28°), the rocker will be horizontal. At about that point the kick-over lugs 19k will begin to abut the left shoulders 22s. Hence further rotation of the spindle and rocker 20 will not only move the operating lever 26 and further tension and move the spring 15 toward overcenter position but also it will rock the switching member 22 oppositely toward overcenter position. As a result of the combined movements of the switching member and the operating member both approaching the overcenter position, but in opposite directions, the overcenter movement is accelerated as the critical point in the movement of the spindle is reached. As the critical overcenter point is reached both the operating and operated parts are moving in the direction that the spring will snap them. Thus movement of the spindle through a lesser angle accomplishes overcenter snap action easier than in conventional overcenter snap switches.

When the spring has been compressed and has moved so that the line of action thereof passes across the line between the then position of strut 23 and the axis of the spindle, the pressure of the overcenter spring will be reversed to move the switching member 22 with a snap action to a new position of rest. In other words, in Fig. 1 such overcenter action would tend to move the switching member 22 in counter-clockwise direction. Such movement of the switching member will rotate the contact supporting discs 30, 31 and in turn will cause movement of the contact members 32, 33 carried thereby. In this way the bridging contact members 32, 33 can be moved from one position to another to turn the switch "on" and "off" or from engagement with one set of contacts to engagement with another. The stationary contacts are indicated at 34, 35 in Fig. 2.

By coordinating the positive kick-over feature together with the rocking member and operating lever combination in the novel manner as described, a lighter switch spring can be used than otherwise. This lengthens the life of the switch by reduced frictional wear and hammering of the parts. At the same time movement of the operating spindle through a lesser angle than heretofore causes operation of the switch so that it can be used in places where conventional constructions would not operate.

Many modifications within the scope of the art, and application of the invention to other switches of different details of construction, will be apparent to those skilled in the art. Therefore I do not limit it to the specific embodiment illustrated.

What is claimed is:

1. An electric snap switch comprising an overcenter mechanism, means to actuate said mechanism comprising a lever pivoted about a fixed pivot and engaging with said over-center mechanism to swing the same over-center, operating means rockable about a fixed pivot displaced from said first fixed pivot, and a driving connection between said rockable means and said lever to cause movement of the lever by said rockable means, movable contact means, and means to

mount said contact means pivotally around the same axis as said operating means for movement independently of said operating means with a snap action.

5 2. An electric snap switch as claimed in claim 1 and having a pin and slot driving connection between said rockable means and said lever to cause movement of the lever by said rockable means, said pin and slot connection being between the axis of said rockable means and the axes of said lever.

10 3. An electric snap switch comprising an overcenter mechanism, contact means moved with a snap by said mechanism, means to actuate said mechanism comprising a lever pivoted about a fixed pivot and engaging with said over-center mechanism to swing the same over-center, operating means rockable about a fixed pivot, and a driving connection between said rockable means and said lever to cause movement of the lever by said rockable means, an enclosing casing having cooperating parts, bearings for said rocking member pivot each bearing being formed partly in one and partly in another of said casing parts at the abutting edges thereof, said casing forming a substantially complete enclosure for said switch, which is dust proof.

15 4. An electric snap switch comprising an overcenter mechanism, contact moving means moved with a snap by said mechanism, contact means moved by said contact moving means, means to actuate said mechanism comprising a lever pivoted about a fixed pivot and engaging with said over-center mechanism to swing the same over-center, operating means rockable about a fixed pivot displaced from said first fixed pivot, and a driving connection between said rockable means and said lever to cause movement of the lever by said rockable means, said contact moving means and rockable means being pivoted about the same axis.

20 5. An electric snap switch comprising an overcenter mechanism, contact moving means moved with a snap by said mechanism, contact means moved by said contact moving means, means to actuate said mechanism comprising a lever pivoted about a fixed pivot and engaging with said over-center mechanism to swing the same over-center, operating means rockable about a fixed pivot, and a driving connection between said rockable means and said lever to cause movement of the lever by said rockable means, said contact moving means and rockable means being pivoted about the same axis, and a casing for said switch having cooperating parts, an open bearing formed in one part, a pivot for said lever held seated in said bearing by the pressure from said over-center mechanism.

25 6. A switch as claimed in claim 5 having cooperating bearing surfaces in the abutting edges of said casing parts forming a bearing for the pivot of said rockable means.

30 7. An electric snap switch comprising overcenter switch means, a switching member, a lever for operating said over-center means, a fixed pivot for said lever, rockable means having a connection with said lever for moving it, a fixed pivotal axis for said rockable means, means moving with said rockable means and engageable with said switching member when said rockable means has moved approximately through half its angle of movement to start said switching member toward over-center position, whereby the over-center action is accelerated by the simultaneous movement of said over-center means and

said switching member toward over-center position.

8. An electric switch as claimed in claim 7 wherein the fixed axis for the rockable means is a spindle, in combination with a casing having cooperating parts, bearings which are each partly formed in adjacent edges of the side walls of the casing for said spindle and a portion of the spindle extending at the side of the casing for operating the switch.

9. An electric switch as claimed in claim 7 wherein the rockable means comprises a two part spindle on which is mounted a rocking member that joins said spindle parts for operation as a unit.

10. A switch as claimed in claim 9 wherein said lever moves between said spindle parts.

11. A switch as claimed in claim 7 having a pin

and slot connection between said rockable means and said lever, said connection being located between the axes of said lever and said rockable means.

12. A switch as claimed in claim 7 mounted in a casing having cooperating parts, an open bearing in one of said casing parts for the pivot of said lever, said over-center means holding said pivot seated in said bearing.
